The ornamental design for a calculator having advertising space for a shopping cart handle, as shown and described.

DESCRIPTION

FIG. 1 is a perspective view of a calculator with advertising spaces for a shopping cart handle, showing my new design; FIG. 2 is a front view; FIG. 3 is a bottom view; FIG. 4 is a top view; FIG. 5 is a left side view; FIG. 6 is a right side view; FIG. 7 is a rear view; FIG. 8 is a front view of a second embodiment of my new design, the left side, right side, and rear views thereof being identical to FIGS. 5, 6, and 7, respectively; FIG. 9 is a bottom view of the second embodiment; FIG. 10 is a top view of the second embodiment; FIG. 11 is a bottom view of a third embodiment of my new design, the front view thereof being identical to FIG. 2; FIG. 12 is a top view of the third embodiment; FIG. 13 is a left side view of the third embodiment; FIG. 14 is a right side view of the third embodiment; and, FIG. 15 is a rear view of the third embodiment. The broken line showing of advertising spaces on FIGS. 1-3 are for illustrative purposes only and form no part of the claimed design.
